(57) **CLAIM**

The ornamental design for a tire, as shown and described.

DESCRIPTION

FIG. 1 is a right side perspective view of tire showing my new design;

FIG. 2 is a second right side perspective view thereof; FIG. 3 is a front elevational view thereof; the rear elevational view being a mirror image thereof; and, FIG. 4 is a right side elevational view thereof; the top, bottom and left side elevational views being mirror images thereof.

In the drawings, the broken lines showing of the tire tread, inner bead and hub depict boundaries of the claim. All other broken lines shown in the drawings depict environmental subject matter only and form no part of the claimed design.

1 Claim, 4 Drawing Sheets---
